UNITED STATES PATENT OFFICE.

LE ROY A. CRUMLEY, OF NEW YORK, N. Y., ASSIGNOR TO J. H. WHITE MANUFACTURING COMPANY, OF BROOKLYN, NEW YORK, A CORPORATION OF NEW YORK.

DESIGN FOR AN ARM FOR LIGHTING FIXTURES.

Application filed March 11, 1927. Serial No. 21,101. Term of patent 3½ years.

To all whom it may concern:

Be it known that I, LE ROY A. CRUMLEY, a citizen of the United States, residing in the borough of Manhattan, in the city, county, and State of New York, have invented a new, original, and ornamental Design for an Arm for Lighting Fixtures, of which the following is a specification, reference being had to the accompanying drawing, forming part thereof.

Figure 1 is a side elevation of an arm for lighting fixtures showing my new design, and

Fig. 2 is a front elevation of the same.

I claim:

The ornamental design for an arm for lighting fixtures as shown.

LE ROY A. CRUMLEY.
